UNITED STATES PATENT OFFICE.

FRANK W. NEVENS, OF MINNEAPOLIS, MINNESOTA.

COLLAR-FINISHING MACHINE.

1,134,548.

Specification of Letters Patent. Patented Apr. 6, 1915.

Application filed May 4, 1914. Serial No. 836,158.

To all whom it may concern:

Be it known that I, FRANK W. NEVENS, citizen of the United States, resident of Minneapolis, county of Hennepin, State of Minnesota, have invented certain new and useful Improvements in Collar-Finishing Machines, of which the following is a specification.

My invention relates to that class of finishing machines used for finishing turn down collars. These have usually been finished on a curved plate having an edge upon which the fold of the collar is seated, the iron being moved back and forth over the fold during the finishing operation. I have found that a sharp bend or fold is made in the collar, resulting in the cracking and breaking of the fabric and making it extremely difficult to pull a tie back and forth between the folds of the collar in adjusting it to make the knot.

The object, therefore, of my present invention is to provide a finishing support for a collar which will cause a comparatively broad rounded bend or fold to be made in the collar and thereby prevent the cracking or breaking of the fabric in ironing.

A further object is to form a broad rounded fold in the collar which will provide a considerable space between the inner and outer fold in which the tie will lie and have freedom of lengthwise movement for adjustment in tying.

A further object is to increase the capacity of the finishing machine by providing a construction which will permit the placing of a collar upon one finishing support while the operation of finishing is being performed on another support.

Other objects of the invention will appear from the following detailed description.

The invention consists generally in various constructions and combinations, all as hereinafter described and particularly pointed out in the claims.

In the accompanying drawings forming part of this specification, Figure 1 is a front view of a finishing machine embodying my invention, Fig. 2 is a detail sectional view of the finishing head and support, Fig. 3 is a plan view of the finishing device, Fig. 4 is a detail sectional view, showing the preferred construction of the collar support.

In the drawing, 2 represents a suitable frame, having a top 3. Upon this top a base 4 is mounted and provided with a hub 5.

The base 4 has a bearing 6 for a revoluble member 7 seated thereon. This member is preferably in the form of a flattened ring held in place on the base by a shoulder 8 and provided with operating handles 9. Upon this member 7 an upright collar support 10 is mounted, curved to correspond to the curvature of a collar and of suitable diameter and preferably less than a full circle and greater than a semi-circle. I prefer to provide two of these supports on the member 7, arranged opposite one another in position to allow the operator to place a collar on one support while another collar is being finished upon the other support. The supports are preferably made of metal and each support has a comparatively broad, curved edge 11 forming a seat for the fold of the collar, the outer surface being inclined inwardly, as indicated at 12, while the inner surface, as indicated at 13, is substantially straight. The effect of this construction is to finish the inner folds flat against the inner surface of the support, while the outer fold is bent inwardly so that the lower edges of the collar will be close together, while in the fold therein sufficient space will be provided to allow a tie to slide smoothly and easily therein and greatly facilitate the forming of the knot. Oftentimes ties of certain material will stick between the folds of the collar and the tie will be torn in attempting to pull it to its tying position. All this objection to the ordinary way of finishing a collar is avoided and by making the broad, curved fold in the collar, all danger of cracking and breaking the fabric at the point where the fold is made is eliminated, and the life of the collar is greatly prolonged. Obviously this form of support can be modified in various ways, my purpose being to widen the fold to such an extent that breakage of the collar will be prevented and the tie will slide easily therein.

Suitable means are provided for locking the collar support temporarily during the finishing operation. Such means may consist of a pin 14 carried by a spring strap 15 that is secured at one end to the frame of the machine, as at 16, and projects beyond the frame at its other end in position where the operator can bend the strap downward and withdraw the pin from the socket 17 in the base and member 7, thereby allowing the member 7 to be revolved to shift the position of the collar supports. With each movement

of the revolving member the pin will slip into the socket 17 as soon as they are in register and lock the member against further movement in either direction. This locking means may, of course, be modified in any suitable way.

An upright shaft 18 projects through the hub 5 and supports a head 19 on which irons 20 are mounted, said irons having grooves 21 therein and heated by an electric current delivered through conductors 22 in the usual way, said grooves 21 being adapted to receive the upper edge of the collar support preparatory to the finishing operation. The heads 20 are mounted to rock on bearings 20' and are provided in their outer ends with pins 20''. Springs 21', preferably in flattened form, are pivoted at one end on the head 19 and have downwardly turned outer ends 21'' which bear on the pins 20'' and hold the irons down with a yielding pressure but allow them to rock in passing back and forth over the ends of the collar. A standard 23 is arranged below the collar support and has bearings for the shaft 18 therein, and a collar 24 is splined on said shaft and held against longitudinal movement by the standard 23, but allows the shaft to slide freely therein. This collar is provided with an arm 25 connected by a pitman 26 with a gear 27 that is driven through a gear 28 and a belt 29 from a motor 30. A rocking movement will thereby be imparted to the collar 24 and the shaft 18, which movement will be continuous as long as the machine is in operation. A lever 31 is pivoted in said frame and has a fork at one end connected with a collar 32 on the shaft 18 which bears on a spring 33 carried by said shaft. A treadle 34 is pivoted in the machine frame and connected by a rod 35 with the lever 31, and when this treadle is depressed the shaft 18 will be pulled down against the tension of the spring 33 to seat the irons on the collar support, and the rocking of the shaft will move the irons back and forth over the collar until the finishing operation is completed. I prefer also to provide a rod 37 connected at one end 50 with the treadle and slideable in the frame at its opposite end and having an adjusting nut 37' by means of which the stroke of the treadle is regulated and a spring 37'' is coiled on the said rod and attached to said frame and to the treadle and put under tension when the treadle is depressed for returning the treadle to its normal position and raising the finishing heads to a point out of contact with the collar support. A stop 60 38 is preferably provided in the collar support against which one end of the collar is seated, the other end of the collar extending to a point near or at some little distance from the other end of the support, depending upon the size of the collar, the support

being made of sufficient length to accommodate any size of collar. For the purpose of holding the end of the collar down on the support I prefer to provide a clip 39 secured to the lower portion of the support 70 and having a hooked end to extend over the upper edge of the support and engage the end of the collar to prevent it from tilting upwardly during the finishing operation.

To use the machine, the operator will 75 place a collar on the support adjacent to the position where the operator is standing, and then turn the revoluble member 7 until the support is beneath the irons. Then by operating the treadle the irons will be moved 80 into contact with the collar and kept in that position until the collar is properly finished. While the finishing operation is being performed, another collar is being placed on the second support, ready to be moved beneath 85 the irons when the revolving member is again operated.

In various ways the details of construction herein shown and described may be modified and still be within the scope of my 90 invention.

I claim as my invention:

1. In a collar finishing machine, a pair of collar supports having edges forming a seat for a collar placed thereon, a member upon 95 which said supports are arranged, a finishing head adapted to engage the fold of a collar placed on said supports, said member being revoluble around the center of their supporting base, whereby one support may 100 be positioned to receive a collar, while the other support is in the finishing position beneath said head.

2. The combination, with a collar support having an edge forming a seat for a collar, 105 of a continuously oscillating finishing head and mechanism for moving said head into engagement with the fold of a collar on said support, said mechanism including a shaft having a longitudinal and rotary movement. 110

3. The combination, with a collar support, of an upright shaft, and means for rocking the same, a finishing head having a rocking movement on its support, means yieldingly resisting said rocking movement and means 115 for moving said shaft lengthwise to engage said finishing head with the collar on said support or disengages it therefrom.

4. The combination, with a collar support, of a shaft, a finishing head carried by said 120 shaft, and having a rocking movement, a spring device supported by said shaft and having a bearing on said head to yieldingly resist the tilting of said head, and means for moving said shaft lengthwise to seat said 125 finishing head on a collar or remove it therefrom.

5. A collar finishing machine comprising a rotating member, a pair of collar supports thereon having curved rounded surfaces to 130

receive the collars, and an oscillating finishing head mounted adjacent to said supports its axis of oscillation being in the path of movement of the axes of the supports.

5 6. A collar finishing machine comprising a rotating member having a pair of curved collar supports thereon, and an oscillating ironing head mounted for alternate engagement with said supports.

10 7. A collar finishing machine, comprising, in combination, an oscillating ironing head, a revoluble base, and a plurality of collar supports mounted upon said base, and arranged to be brought beneath said head by the revolution of said base.

15 8. A collar finishing machine comprising a rotating base, a collar support for a turn-down collar thereon, a shaft eccentrically mounted with respect to said base, an ironing head carried by said shaft and adapted to contact with the collar on said support, means for rocking said shaft to oscillate

said head, and means for moving said shaft lengthwise to engage said head with the collar.

25

9. A collar finishing machine comprising a rotating base, collar supports mounted thereon having curved supporting edges in the form of segments of a circle and in opposing relation to one another upon said base, an oscillating ironing head having its base, an oscillating ironing head having its axis eccentric with respect to said base and concentric alternately with said supports during the rotation of said base, and mechanism for engaging said ironing head with the collar on said supports, one support being in position to receive a collar while the other collar is being finished.

In witness whereof, I have hereunto set my hand this 29th day of April, 1914.

FRANK W. NEVENS.
